UNITED STATES PATENT OFFICE.

HORATIO BARNETT, OF MALVERN, ARKANSAS.

HENNERY.

1,089,303.

Specification of Letters Patent.

Patented Mar. 3, 1914.

Application filed July 13, 1911. Serial No. 638,337.

To all whom it may concern:

Be it known that I, HORATIO BARNETT, a citizen of the United States, residing at Malvern, in the county of Hot Spring and State of Arkansas, have invented a new and useful 5 Hennery, of which the following is a specification.

The present invention appertains to a hennery, and aims to provide a novel and 10 improved structure of that nature.

In the accompanying drawing illustrating 15 the preferred embodiment of my invention, wherein it will be understood that various changes or modifications may be made as relates to the detailed construction and arrangement of the parts without departing from the spirit of my invention—Figure 1 is a front elevation of the device. Fig. 2 is 20 a sectional elevation thereof. Fig. 3 is a horizontal section of the same. Fig. 4 is a fragmentary view in side elevation of the hennery. Fig. 5 is a transverse section through one of the nests.

In carrying out my invention, I erect a 25 suitable inclosure or house 1 for the fowls, the same being preferably rectangular in general construction, with the roof properly pitched for suitably shedding or draining the water, which roof is of any suitable wa- 30 ter-proof material, as sheet iron or the like. Suitable doors or closures 2 are hinged to swing laterally thereon with their meeting edges resting when the doors are closed 35 against a vertical strip or jamb-member 2a.

It will be noted that the bottom edges of 40 the doors 2 are removed a short distance from the corresponding edge of the doorway, or threshold, to form or leave an opening 12 at that point for aiding ventilation as will be readily appreciated; also through 45 this opening sedimentary matter including the fowl droppings, may be suitably removed. Regarding this latter, however, facilities are provided for the reception of such accumulations as they are removed from the hennery which will be described hereinafter.

The inclosure or house is provided with a 50 relatively thick floor or bottom 3, preferably of tiling, brick or concrete, or other material of a moisture proof nature for the comfort of its occupants and improved sanitary conditions. The bottom is designed to rest flush on the ground. The side and back 55 walls of the house or hennery are preferably of sections 4 of galvanized sheet iron, with

parallel lapping edge-portions, said lapping portions being braced or reinforced by horizontal iron bars 5, all being suitably fastened or bolted together as at 6. The sides 60 terminate short of the front edge of the bottom, and the doors 2 are hinged to the front edges of the sides. The upper front portion of the hennery or house is of suitably meshed wire-netting 7 to aid in producing 65 air-circulation or ventilation as well as to admit light and sunshine as will be readily understood. Also in the lateral walls of the hennery or house, near the bottom and at the front thereof, are provided openings or 70 wickets 9, suitable for the chickens or fowls to pass in and out. Also in one side of the hennery or house is provided a suitable doorway and its closure 10, as an entrance or means of access by a person thereto. 75

The doors 2 are spaced above the bottom to provide a cleanout opening extending from side to side, the bottom extending beyond the doors, and an angle iron member 11^a having one flange secured to the lower 80 face of the bottom along its front edge flush with the lower face of the bottom, and having its other flange spaced from and forming an open ended trough with the forward edge of the bottom to readily receive the 85 droppings of the chickens or fowls or other sedimentary accumulations as the same are swept or removed from the hennery, out through the door way at the front thereof. The edge of the upright flange of the angle 90 iron member 11^a lies in the plane of the upper face of the bottom.

Suitable nests 11 are provided within the hennery or house for the chickens or fowls to occupy for laying or setting purposes as 95 will be readily appreciated. These nests are contrived each of suitable wire-netting or fabric preferably in receptacle like formation, the thus formed wire receptacles being secured in position either by nailing or se- 100 curing to the floor or bottom of the hennery or by suitably supporting the same in elevated position upon bent or right angled rods or brackets 14 secured to said bottom also to the walls of the hennery or house, as 105 clearly seen in Figs. 1, 2 and 3. Suitable roosts 15 and 16 are also provided for the fowls or chickens, the roost 15 being prefer- 110 ably in ladder-form and disposed diagonally within the hennery or house, its ends being suitably secured, in any preferable way to the inner surface of one side thereof and to

the floor, respectively, more especially as shown in Fig. 1. The roost 16 is preferably in the form of rods or members 16^a, with their ends secured to one end of the house or inclosure 1 and supported in suspending rods or members 16^b, respectively, the latter depending from the roof of the inclosure or house 1; upon which members 16^a are suitably supported transverse bars or 10 roosts proper 16^c.

What is claimed is:

A henry embodying a relatively thick and solid bottom designed to rest flush on the ground, sides and a back secured to the 15 bottom, the sides terminating short of the front edge of the bottom, a pair of doors hinged to the front edges of the sides and spaced above the bottom to provide a clean-

out opening extending from side to side, the bottom extending beyond the doors, and an 20 angle iron having one flange secured to the lower face of the bottom along its front edge and flush with the lower face of the bottom, the angle iron member having its other 25 flange spaced from and forming an open ended trough with the forward edge of the bottom, the edge of the last mentioned flange lying in the plane of the upper face of the bottom.

In testimony that I claim the foregoing 30 as my own, I have hereto affixed my signature in the presence of two witnesses.

HORATIO BARNETT.
